Application July 13, 1938, Serial No. 78,448

Term of patent 14 years

To whom it may concern:

Be it known that we, James Frederick Barnes and Jean Otis Reinecke, citizens of the United States, residing at Chicago, in the county of Cook and State of Illinois, and Roy W. Johnson, a citizen of the United States, residing at Milwaukee, in the county of Milwaukee and State of Wisconsin, have invented a new, original, and ornamental Design for a Room Thermostat, of which the following is a specification, reference being had to the accompanying drawing, forming a part thereof, and in which:

Figure 1 is a perspective view of a room thermostat showing our new design;

Figure 2 is a side elevational view thereof; and
Figure 3 is a bottom plan view.

We claim:

The ornamental design for a room thermostat, as shown.
